COUNTER ACTUATING MECHANISM FOR
TICKET PRINTERSThomas A. Keen, Belmont, and Ernest M.
Whitley, San Carlos, Calif.Original application February 2, 1948, Serial No.
5,874. Divided and this application August 20,
1951, Serial No. 242,676

2 Claims. (Cl. 235—91)

1

This invention relates to ticket printers of the kind employed in connection with the sale of tickets under the pari mutuel system of wagering on races and this application is a division of our co-pending application entitled "Ticket Printer," filed February 2, 1948, Serial No. 5,874, now abandoned.

Conventional ticket printing machines used in connection with the pari mutuel system comprise a bank of numbered keys each number representing an entry in a race. The function of the machine is to print a ticket bearing the number of a selected key on a ticket strip, then to advance, shear and eject the ticket as well as to produce a visible registration of the number of tickets sold for each entry and the total number of tickets issued.

According to conventional practice each ticket is printed to display the number of a race upon which the wager was placed, the date, a code number or symbol and the entry number determined by the key depressed. Such machines include means for changing the date, race number and code symbol printed, but the present invention is not concerned with such mechanism and the following description will be confined to the means controlled by depression of a numbered key to establish a setting of the entry number to be printed upon the ticket and particularly to set the mechanism which upon operation of the machine will effect actuation of a counter corresponding to the depressed key as well as of a total counter and related mechanism.

An object of the present invention is to provide a machine capable of performing all of the required functions of ticket printers of this kind through a relatively simple set of mechanisms. A further object of the invention is to provide a ticket printer having keys acting mechanically upon being depressed to establish conditions in the machine requisite to its printing a ticket of a selected number and actuating a corresponding counter. Still further and more specific objects and advantages of the invention are made apparent in the following specification wherein the invention is described in detail by reference to the accompanying drawings.

In the drawings:

Fig. 1 is a plan view of a machine embodying the present invention with the top portion removed and with portions broken away and illustrated in section;

Fig. 2 is a sectional view taken on the line II—II of Fig. 1;

Fig. 3 is a sectional view taken on the line III—III of Fig. 1;

Fig. 4 is a fragmentary section on the line IV—IV of Fig. 3;

2

Fig. 5 is a section taken on the line V—V of Fig. 4;

Fig. 6 is an elevation of the mechanism shown in Fig. 4 as viewed from the plane VI—VI; and

Fig. 7 is a front elevation with forward part of the machine being removed and parts broken away to illustrate various parts of the mechanism.

The machine herein illustrated is supported by a base plate 10 and enclosed by a housing 11 with a hinged cover 12 adapted to be secured in closed position as by a key-actuated lock indicated at 13. The principal parts of the ticket printing, shearing and ejecting mechanism are supported between parallel spaced vertical plates 14 in the main portion of the housing. A ticket strip 15 is fed upwardly through a slot 16 in the bottom of the housing and between the plates 14 where it is trained over a ticket-advancing roller 17 with projections 18 thereon spaced to extend through suitably spaced perforations in the strip. From the roller 17 the ticket passes between guide members 19 and 20, then under a ticket printing head 21, and past a shearing blade 22 adapted to cooperate with a stationary blade 23. An ejector roller 24 is positioned to engage the sheared ticket and to advance it through a slot 25 formed to open through the cover of the housing.

A motor 26, as shown in Fig. 1, acts through reduction gearing contained in a housing 27 to drive the driving member 28 of a single cycle clutch through suitable gears 29 and 30. The clutch, which is of a conventional type, is held in disengagement by an armature 31 of a solenoid 32. This armature intercepts a finger 33 which projects from the driven part of the clutch and upon energization of the solenoid 32 the armature is retracted momentarily to permit the clutch-driven part to rotate through a single complete cycle. This rotation is imparted to a main shaft 34 which, as illustrated in Fig. 2, extends through the space between the supporting plates 14 and carries between said plates a cam 35. The extended end of the shaft 34 carries, as illustrated in Fig. 3, a large ticket-feed cam 36 as well as means presently to be described for actuating counter mechanism.

In operation of the parts thus far described, the motor is rotating continuously and upon closing of a circuit to the solenoid 32 the driven part of the clutch imparts a single complete rotation to the main shaft 34. The cam 35 on this shaft first engages a lever 40 pivotally supported on a shaft 41 and having a finger 42 carrying adjusting screws 43 for engagement with a printing platen 44. The platen 44 is mounted for sliding movement in a guide 45 and is normally held in a

retracted position by a spring 46. Upon downward swinging of the lever 40 under influence of the cam 35 the platen is raised against the tension of the spring 46 and presses the ticket strip 15 against the type faces on the ticket-printing head 21 to imprint on the ticket the characters represented by the registering type faces. As the main shaft 34 continues to rotate, the ticket-feed cam 36 (Fig. 3) on its outer end engages a roller 47 on a slide bar 48. At one end this bar is slotted to embrace the main shaft 34, thus to be supported thereby and to be free for sliding action thereon. At its opposite end, the slide bar carries a rack 49 normally retracted by a spring 49a and resting on a guide roller 50 arranged to retain it in meshing engagement with a gear 51. The gear 51 is formed as a part of disc 52 and the gear and disc are freely rotatable on the end of a shaft 53 which carries the ticket advancing roller 17. As best shown in Figs. 4, 5 and 6, movement of the rack 49 toward the left as viewed in Figs. 3 and 6 will rotate the gear 51 and disc 52 in a clockwise direction. During this rotation, a pawl 54 secured as by a pin 55 to the disc 52 engages the notched periphery of a ratchet disc 56 keyed to the shaft 53 to drive the shaft and to impart rotation to the ticket advancing roller 17, a distance corresponding to the length of one ticket. A pawl 57, pivoted as by a pin 58 to the stationary plate 14, also engages the periphery of the ratchet disc 56 to prevent reverse rotation thereof when the rack bar 49 is retracted under influence of the spring 49a. Both pawls 54 and 57 are biased toward the ratchet disc 56 as by springs illustrated at 59. As the ticket strip is advanced beneath the ticket-printer head a distance corresponding to the length of one ticket the upper end of the ticket strip, just having been printed upon, is advanced beyond the shearing blade 22 and into contact with the ejecting roller 24. During the final part of the rotary movement of the main shaft 34 the cam 35 thereon engages a lever 60 also pivoted on the shaft 41 and carrying adjusting screws 61 engageable with the lower end of the shear blade 22. A spring 63 normally tends to retract this blade. The action of the lever 60 under influence of the cam 35 advances the shear blade 22 upwardly to cooperate with the stationary blade 23 in shearing the ticket strip. A spring 64 forms a connection between the levers 40 and 60 to insure that they remain in close contact with the cam 35.

The ejecting roller 24, which is preferably of rubber or other resilient material, is driven continuously during the operation of the main shaft through a train of gears shown at 67 in Fig. 1 as connecting with a shaft 68 upon which the ejector roller is mounted. A flat spring 69 is preferably employed for holding the ticket in contact with the ejecting roller and may have an anti-friction roller 70 normally engaging the surface of the ejector roller if desired. The ticket-printing head 21 comprises a plurality of multi-faced type discs rotatably mounted on a common shaft 75 supported between the plates 14 as by clamping members 76. As previously stated, these type discs are arranged for printing race number, date, code numbers and the number of the entry represented by the printed ticket. The present invention is concerned particularly with the entry disc, which is that indicated at 77 at the left hand side in Fig. 1. This disc 77 carries a gear 78 by means of which it may be rotated or held in any set printing position. The type characters on the periphery of the disc 77 are the

numerals 1 to 12, inclusive and a "T"—representing "test" used only when a ticket is printed during a test operation of the machine. The type disc 77 is rotated to effect positioning of any desired type character in printing position by a rack 79 held in mesh with the gear 78 by an idler roller 80 disposed on one of the supporting plates 14. This rack is adjustably connected with a link 81 by means of screws 82 and the link 81 is pivotally connected as by a pin 83 with a post 84. The post 84 is carried by and extends upwardly from a slotted plate 85, and this plate is secured to a shaft 86 rotatably disposed between spaced vertical supporting plates 87 between which the key control mechanism of the machine is also disposed.

The slotted plate 85 is normally held in a raised position as by a spring 89. Disposed between the side plates 87 are a plurality, in this case 13, of key stems 90 extending all of the way through the housing and having tabs 91 at their upper ends appropriately numbered as indicated in Figure 1 from 1 to 12, inclusive, the 13th key stem bearing the character "T." Each of the key stems 90 is normally urged upwardly as by a spring 92 interposed between a pin 93 on the stem and the bottom of the housing. When any one of the stems is depressed it is held in its depressed position by a bar 94 secured to a shaft 95 pivotally supported between the side plates 87 and urged to swing upwardly as by a spring 96. Upon depression of any key against the tension of its spring 92 it will be latched in its depressed position by the engagement of a lug 97 projecting from a flattened side of the key stem and engageable beneath the bar 94. Any subsequently depressed key will, of course, swing the bar 94 downwardly to release the first key before it is itself engaged in depressed position so that one key and only one key will occupy the depressed position. The depressed key establishes the setting of the numeral to be printed by the entry disc 77 on the printing head when the machine is operated and also determines which of a plurality of counters will register the subsequent operation of the machine. In order to establish the entry number to be printed on the ticket, each of the key stems 90 is provided with a pin 99 and these pins, as shown in Figs. 2 and 7, are arranged at gradually varying heights and disposed above the plate 85 where the key stems 90 pass through notches 100 in this plate. Consequently upon depression of any key the plate is swung downwardly and the distance that the plate is swung downwardly depends upon the key depressed, so that if number 1 key is depressed the plate will be swung a distance sufficient to cause the rack 79, Fig. 2, to rotate the entry disc until the number 1 type character thereon registers in the printing position. As the number 2 key and number 3 key swing the plate 85 downwardly correspondingly greater distances, the number 2 or 3 type character on the entry disc 77 may likewise be brought into printing registry, and so on through key number 12. The 13th key marked "T" serves to bring the character "T" into printing registry.

A plurality of mechanical counters 101 are supported in a plate 102 which extends between the side plates 87, there being one such counter for each of the keys on the machine. Sight openings 103 are provided in the top of the housing above the counters to enable the reading of the numbers displayed thereby. Each of the counters 101 is provided with an actuating lever

104 (Fig. 4) adapted to advance the counter upon being swung upwardly. Plungers 105 are loosely supported in the plate 102 for vertical reciprocation and are supported against downward sliding movement by adjustable collars 106. Beneath the plate 102 a frame 107 is supported on a shaft 108 pivotally mounted between plates 87. Frame 107 carries the channel member 109, and pins 110 are slidably mounted through perforations in said channel. Pins 110 are, as best shown in Fig. 1, each bent to a U-shape with one leg shorter than the other so that the short leg passes through only one flange of the channel 109, thus preventing rotation of the pins and presenting a right angular portion aligned with one of the key stems 90. A spring 111 serves to retain each of the pins 110 in a retracted position. Upon depression of any one of the keys a wedge 112 (see also Fig. 2) on the key stem engages the right angular part of the pin 110 and advances the pin forwardly until its forward end projects to a position beneath the plunger 105, in which position the plunger will be urged upwardly and the corresponding counter 101 will be actuated when the frame 107 is swung upwardly. The frame 107 is swung upwardly once for each ticket issued by the machine by a lever 114, shown in Fig. 3, fixed against rotation to a projecting end of the shaft 108 which supports the frame 107 and connected as by a link 115 with an eccentric pin 116 carried on the end of the main shaft 34 of the ticket printing mechanism.

Zeroizing levers 118 are also provided on the counters 101 and may, as shown in Figs. 2 and 7, carry pins 119 received in slots of a slideable bar 120, which extends transversely of the machine. A suitable opening (not shown) may be provided in the side wall of the machine so that a key or instrument may be inserted therethrough and engaged with an end of the bar 120 to slide it in a transverse direction and actuate all of the zeroizing levers simultaneously for the purpose of setting all of the counters to their zero position.

The pins 110, which actuate the counters corresponding to keys 1 to 12, inclusive, are identical in construction, but the corresponding pin for the test key has, as illustrated in Fig. 1, a plate 124 secured to its forward end having a perforation 125 therein. Ordinarily perforation 125 is out of alignment with the bottom of the plunger 105 corresponding to the counter actuated by this pin. This is a "total" counter and serves to register tickets issued for all the keys 1 to 12 inclusive. Therefore, when the machine is operated to issue a ticket, not only will the counter corresponding to the number of the ticket issued be actuated, but the "total" counter will also be actuated by the upward movement of the plate 124. It is desired in some cases to test the operation of the machine before tickets are sold, and this is accomplished by depressing the "T" key. In this event the wedge 112 on the "T" key stem 90 will advance the pin 110 with the plate 124 on its forward end to a position where the hole 125 therein will register with the bottom end of the plunger 105. Consequently the ticket issued will bear a character "T" rather than a number and none of the counters will have been actuated.

When any one of the key stems 90 is depressed, its lower end projects downwardly through the bottom of the machine and may be employed to close a switch 128, shown in Fig. 2 as supported by a bar 129 carried by posts 130 extending downwardly from the bottom plate of 75

the machine. Closing of this switch may be employed in connection with the sending of electrical impulses to totalizing machinery which is generally associated with a plurality of ticket-printing machines but does not form a part of the present invention.

Depression of a selected key for issuing a ticket with the number corresponding to the key selected, as herein described, serves to set the entry disc on the printing head to the proper position and serves also to select or establish the counter that will be actuated upon issuance of the ticket. The actual operation of the machine to issue a ticket is, however, initiated by closing of a switch 132, also supported by the bar 129 beneath the machine. The switch 132, which completes a circuit to the solenoid 32 for initiating a single cycle operation of the machine, is adapted to be closed by a plunger 133. This plunger extends upwardly through the machine and is connected at its upper end with an actuating bar 134, as shown in Figs. 1 and 3. A spring 135 normally retains the post and actuating bar in a raised position and the bar 134 is pivoted as by a screw 136 to a bracket 137. A resilient bumper 138 limits the downward movement of the actuating bar but permits it to be moved downwardly a distance sufficient to cause closing of the switch 132 by the lower end of the plunger 133.

We claim:

1. In a ticket printing machine comprising a plurality of depressible keys for selecting type characters to be printed, counters for registering the number of tickets printed for each key and means for selectively actuating said counters comprising, a reciprocable plunger operatively associated with each counter, a pivoted frame, a plurality of normally retracted pins on said frame, means associated with each key to advance one of said pins upon depression of the key to a position of registry with the plunger corresponding to the same key, and means effective upon each ticket issuing operation of the machine to swing said pivoted frame to operate the selected counter.

2. In a ticket printing machine comprising a plurality of depressible keys for selecting type characters to be printed, counters for registering the number of tickets printed for each key and means for selectively actuating said counters comprising, a reciprocable plunger operatively associated with each counter, a pivoted frame, a plurality of normally retracted pins on said frame, a stem for each key having a wedge shaped portion engageable with to advance one of said pins upon depression of the key to a position of registry with the plunger corresponding to the same key, and means effective upon each ticket issuing operation of the machine to swing said pivoted frame to operate the selected counter.
